Term of patent 14 years

(Cl. D15—3)

FIG. 1

The dominant features of the design reside in the portions shown in full lines. The dotted lines are for illustrative purposes and show fragmentary portions of a chair.

We claim:

The ornamental design for a back rest for dental chair or similar article, as shown and described.
